EX

OR D 21,096

DESIGN.

C. A. WRIGHT.
PHOTOGRAPHIC CARD.

No. 21,096.

Patented Oct. 6, 1891.

UNITED STATES PATENT OFFICE.

CHARLES A. WRIGHT, OF PHILADELPHIA, PENNSYLVANIA.

DESIGN FOR A PHOTOGRAPHIC CARD.

SPECIFICATION forming part of Design No. 21,096, dated October 6, 1891.

Application filed April 27, 1891. Serial No. 390,685. Term of patent 7 years.

To all whom it may concern:

Be it known that I, CHARLES A. WRIGHT, of the city of Philadelphia, county of Philadelphia, State of Pennsylvania, have invented and produced a new and original Design for a Photographic Card, of which the following is a specification.

My invention has reference to designs for cards suitable for photographic and other purposes; and it consists of certain improvements, which are fully set forth in the following specification and shown in the accompanying drawings, which form a part thereof.

My improved design is clearly shown in the accompanying drawings, in which Figure 1 is a perspective view of a card embodying my invention. Fig. 2 is a plan view of same, and Fig. 3 is a cross-section of same on line *x-x*.

A is the body of the card, and has the four right-angled corners C. The edges between the right-angled corners are made with re-

verse curves, as indicated at B. If the card is oblong, its curved portions will be greater in one direction of the card than in the other, as shown. All of the edges are beveled, as at D, and said beveled edges are ornamented by gilding or suitable coloring, and preferably highly polished.

The essential features of the design are the right-angled corners C, with the intermediate curved portions upon the edges.

Having now described my new design, what I claim as new, and desire to secure by Letters Patent, is—

The design for a photographic card, as herein described and shown.

In testimony of which invention I have hereunto set my hand.

CHARLES A. WRIGHT.
